UNITED STATES PATENT OFFICE.

FREDRICH GEBHARDT, OF ALLIANCE, OHIO.

METALLIC TRUCK FOR RAILROAD-CARS.

No. 840,929.

Specification of Letters Patent.

Patented Jan. 8, 1907.

Application filed May 15, 1906. Serial No. 316,913.

To all whom it may concern:

Be it known that I, FREDRICH GEBHARDT, a citizen of the United States, and a resident of Alliance, in the county of Stark and State of Ohio, have invented a new and Improved 5 Metallic Truck for Railroad-Cars, of which the following is a full, clear, and exact description.

The invention relates to metallic trucks 10 for railroad-cars such as shown and described in the application for Letters Patent of the United States, Serial No. 270,787, filed by me on July 22, 1905.

The object of the present invention is to 15 provide a new and improved metallic truck for railroad-cars which is exceedingly strong and durable and arranged to provide a solid bed for the car-body to rest on and to readily accommodate the draw-bar timbers.

20 The invention consists of novel features and parts and combinations of the same, which will be more fully described hereinafter and then pointed out in the claims.

A practical embodiment of the invention 25 is represented in the accompanying drawings, forming a part of this specification, in which similar characters of reference indicate corresponding parts in all the views.

Figure 1 is a plan view of the improvement. Fig. 2 is a sectional side elevation of 30 the same on the line 2 2 of Fig. 1. Fig. 3 is an enlarged transverse section of the same on the line 3 3 of Fig. 1. Fig. 4 is an inverted plan view of the body-bolster. Fig. 5 is a plan view of part of the truck-bolster, and 35 Fig. 6 is a sectional plan view of the journal-box in position on the side frame.

The metallic side frames A are integrally connected with each other by a channel cross- 40 bar B, having flanges B' fastened by bolts C to the inner faces of the side frames A adjacent to the vertical guideways A', formed in the side frames A at the middle thereof and from the top in a downward direction, as 45 plainly illustrated in the drawings. The cross-bar B has its terminals B² extending into and resting on the bottoms of the guideways A', and the said terminals B² are rigidly secured to the said bottoms of the guideways A' by bolts C', the heads of which are 50 countersunk in the upper faces of the terminals B². On the upper surfaces of the terminals B² are mounted to rock in a transverse direction the seats D, each supporting 55 the lower ends of a number of springs E, engaged at their upper ends by a seat D', simi-

lar to the corresponding seat D, and each of the seats D' is mounted to rock on the under side of the end F' of a truck-bolster F, provided at its upper surface and at the middle 60 of the bolster with an annular bearing or seat F², engaging with an annular pivot G', formed on the under side of the body-bolster G, secured in the usual manner to the under side of the car-body of a railroad-car. Each 65 of the side frames A is provided at its outer ends with a journal-box H, in which are mounted to turn the journals of the axles I, carrying the usual car-wheel J.

The body-bolster G is provided at its middle with a longitudinally-extending integral pocket G² for receiving the draw-bar timber K, and on the said body-bolster G are integrally-formed vertically-disposed flanges G³, on which are bolted or otherwise secured the 70 ends of longitudinally-extending beams L, flush on the top with the upper surface of the body-bolster G, so as to form with the latter a solid bed for the car-body of a railroad-car. The flanges G³ are provided with lateral offset 75 lower edges adapted to support the lower edge of the longitudinally-extending beams L, as shown in Fig. 3.

It is understood that the pocket G² extends 80 in a forward direction, while the flanges G³ extend rearwardly and the beams L are secured to the flanges G³ of the front and rear trucks of a car to rigidly connect the two body-bolsters G with each other and form a bed for the car body, as before mentioned.

On the body-bolster G directly above the pivot G' is arranged an integral oil-well G⁴ for containing oil, grease, or other lubricant, and from the bottom of this oil-well G⁴ lead 85 apertures G⁵ to the under side of the pivot G', 90 the apertures G⁵ opening into radial grooves G⁶, formed on the under side of the pivot G'. In the bottom of the bearing F², engaged by the pivot G', are formed concentric annular 95 grooves F³ F⁴, connected with each other at 100 intervals by radial grooves F⁵, so that the lubricant passing from the oil-well G⁴ down through the apertures G⁵ and into the 105 radial grooves G⁶ is readily distributed to the grooves F³, F⁴, and F⁵ in the bearing F² to insure a proper lubrication of the pivot G' in the bearing F². On the top of the truck-bolster F are formed the track-surfaces F⁶, on which are mounted to travel friction-rollers 110 G⁷, journaled in pockets G⁸, depending integrally from the under side of the body-bolster G, as plainly shown in Fig. 3.

The spring-seats D D' and the terminals B² and F' of the cross-bar B and the truck-bolster F are provided at their side edges with recesses engaging vertically-disposed 5 ribs A², arranged integrally on the side walls of the guideways A', and the terminal F' of the truck-bolster F is limited in its upward movement by a yoke N, extending across the open top of the guideway A' and secured by 10 bolts O to the side frames A, as plainly indicated in Figs. 1, 2, and 3. Each of the yokes N is provided at its top with a longitudinally-extending strengthening-rib N', and the under side of each yoke is provided with 15 transversely-extending dovetail-tongues N², engaging correspondingly - shaped dovetail grooves in the upper faces of the side frames A. Each of the spring-seats D D' is provided at its middle with a longitudinally-extending half-round pivot D² D³, engaging 20 seats or bearings B³ F⁷, formed in the corresponding terminals B² F'. The spring-seats D and D' are also provided at their front and rear ends with short flanges D⁴ D⁵ to limit the 25 rocking movement of the said seats by abutting against the corresponding faces of the terminals B² and F'. Each of the journal-boxes H is provided at both sides with vertically-disposed ribs H', of which one fits a 30 corresponding recess in the inner wall of the seat of the journal-box H in the end of the side frame A, it being understood that by the arrangement described the journal-boxes H can be readily used or interchanged at either 35 end of the side frame A, as the corresponding rib H' fits the corresponding recess on the inner wall of the seat in the side frame A. Bolts H', secured to the terminals of the side frame A, engage the outer sides of the journal-boxes 40 H to hold the same against outward movement, and the lateral movement of the journal-boxes is prevented by the usual lugs H³ engaging the front and rear faces of the side frames A.

45 In order to give added strength to the side frames A, truss-ribs A² extend integrally upward and outward from the lower ends of the guideways A', as shown in Fig. 2, to relieve the yokes N of undue strain exerted lengthwise of the side frames A against the sides of the guideways A' from the car-axles by way of the journal-boxes H. The body-bolster G is also provided with truss-ribs G⁹ to reinforce and strengthen the said body-bolster.

50 55 From the foregoing it will be seen that the

truck is formed of comparatively few parts, which can be readily assembled and constitute an exceedingly strong and durable truck. By mounting the body-bolster G on the truck-bolster F in the manner described all friction 60 is reduced to a minimum, and hence cars provided with the improved trucks can readily run around curves without undue friction between the truck-bolster and the car-bolster.

It will also be noticed that by having the 65 spring-seats D D' mounted to rock in a transverse direction the side frames A and the truck-bolster F are relieved of undue strain. By the use of the beams L an exceedingly solid bed is provided for the car-body to rest 70 on; and by having the pocket G² on the car-bolster G proper means are furnished for supporting the timbers of the draw-bar.

Having thus described my invention, I claim as new and desire to secure by Letters 75 Patent—

1. A metallic truck for railroad-cars having a side frame provided at each end with a seat for the journal-box, the inner wall of the said seat being recessed, and a journal-box 80 having lugs on each side and adapted to fit the said recess to allow interchange of a box on either seat.

2. A car-bolster having a flat upper surface, a pocket extending laterally from the 85 central portion of said bolster adapted to receive a draw-beam timber, the upper surface of the pocket being flush with the upper surface of the bolster, and vertical flanges extending from the opposite side of the bolster 90 provided with offset lower edges adapted to support the side beams of a car-body.

3. A car-bolster having a flat upper surface, a pocket adapted to receive a draw-beam timber extending laterally from the 95 central portion of said bolster, the upper surface of the pocket being flush with the upper surface of the bolster, and vertically-disposed flanges extending from the side of said bolster on opposite sides of the line of said pocket, 100 and provided with offset lower edges adapted to support the side beams of a car-body.

In testimony whereof I have signed my name to this specification in the presence of two subscribing witnesses.

FREDRICH GEBHARDT.
